FILLING HEAD FOR FILLING MACHINES

Paul R. Fechheimer, Cincinnati, Ohio, assignor
to The Karl Kiefer Machine Company, Cincinnati, Ohio, a corporation of Ohio

Application March 5, 1952, Serial No. 274,969

13 Claims. (Cl. 226—98)

1

My invention relates to machines for filling containers by introducing a filling substance into them through a spout or nozzle.

In my copending application entitled Pressure-and-Vacuum Filling Machine, Serial No. 164,715, filed May 27, 1950, I have described a machine and filling nozzle construction in which both super-atmospheric pressure and vacuum are employed to effect rapid filling of the bottles or containers. In such a system, a seal is provided about the mouth of the container to draw a vacuum on it, whereupon the filling material is introduced under a pressure greater than atmospheric. A pressure-vacuum system such as this makes it possible to fill the containers more rapidly than is possible with a system operating on pressure or vacuum alone.

In recent years there has developed a wide spread use of flexible containers, such as plastic squeeze bottles, which, due either to their shape, dimensions or materials of construction, are so weak that they will not withstand very much internal vacuum without collapsing or internal pressure without bulging. Rectangular metal cans with spout tops also present the same difficulties. I have found, however, that the difficulties encountered in filling these containers can be overcome by employing the pressure-vacuum filling system taught in my aforementioned copending application.

However, some of these containers, particularly the plastic squeeze bottles, which are often molded in circular cross-section with relatively square shoulders, are weak along their longitudinal axis and incapable of withstanding the normal pressure exerted against the top or mouth of an ordinary container during filling.

It is, therefore, a principal object of my invention to provide an improved filling head for a pressure-vacuum filling machine of the type disclosed in my said copending application which will adapt said machine for use where relatively weak, flexible containers are being filled.

This and other objects of my invention which will be set forth hereinafter or will be apparent to one skilled in the art upon reading this specification, I accomplish by that structure and arrangements of parts of which I shall now describe an exemplary embodiment. Reference is made to the accompanying drawings wherein:

Figure 1 is a partial elevation with parts in section of filling apparatus to which my invention is directed.

Figure 2 is a schematic drawing illustrating various positions assumed by my improved filling head during the filling cycle.

Figure 3 is an elevational view taken along the line 3—3 of Figure 1.

Figure 4 is a view similar to Figure 3, but with the filling head in a different position and with

2

additional parts broken away to show the parts comprising the filling head.

Figure 5 is an enlarged, fragmentary sectional view of the filling spout illustrated in Figures 3 and 4.

Figure 6 is a sectional view taken along the lines 6—6 of Figure 4.

Referring first to Figure 1, I have therein illustrated the main parts of an exemplary filling machine. This machine comprises a central rotating column 1 which bears at its upper end a main head 2, and is connected at its lower end to a table 4 having means 5 thereon for supporting containers 6 and raising and lowering them as may be required. The main head of the apparatus has means 9 for supporting a plurality of filling heads 10 in proper positions to coat with the containers 6 on the movable supporting means 5. The main head has a hollow interior divided by a diaphragm 11 into two chambers 12 and 13, the first of which is a vacuum chamber and the last of which is a chamber for the filling material. The chamber 13 is connected by a vertical conduit 14 inside the column 1, with a conduit 15 leading to a supply tank 17. The connection between pipes 14 and 15 is through a gland 16 which will permit rotation of the conduit 14 with the column 1, as will be understood in this art.

The supply tank 17 for the filling material 18 is arranged to be supplied therewith by a conduit 19 from a suitable source of supply (not shown). Since a super-atmospheric pressure of air is to be built up in the supply tank 17, it is closed by a suitable cover 20; and it will be understood that the filling material will be supplied through the conduit 19 at a pressure sufficient to overcome the internal pressure of the supply tank 17. A float 21 may be provided in the supply tank 17 operating a valve 22 to prevent overfilling and to maintain the supply tank 17 at substantially constant level of the filling material.

The vacuum chamber 12 of the main head 2 is connected by a conduit 23 provided with a gland 24 to permit rotation of the main head with a vacuum chamber and trap 25 mounted on a suitable support 26 on the machine. The vacuum chamber and trap 25 is connected by a conduit 27 to a vacuum pump (not shown). Any increments of filling material coming over into the vacuum chamber and trap 25 through the conduit 23 will be separated from the air stream therein, and will be returned to the supply tank 17 through a pump 28, located at the bottom of the chamber 25, driven by a motor 29 mounted with respect to the support 26 and connected with the supply tank 17 by a conduit 30. It will be understood that pump 28 will operate with sufficient force to overcome the reaction of super-atmospheric pressure on the supply tank 17.

Pressure is built up in the supply tank 17 by connecting it, through a conduit 31 with a source of air or other gas under pressure, such as a pump or tank (not shown). The conduit 31 may be provided with a pressure control valve 32 which will regulate the pressure imposed on the tank 17 and another valve marked 33 which is a solenoid operated cutoff valve for venting the tank 17 in the event of stoppage of the machine.

The construction of the filling head 10 can be best seen in Figure 6. Various constructions are possible, as evidenced by those set forth in my said copending application; and the valving arrangement described herein is exemplary only. The filling head has a body 10a permanently mounted on the supporting member 9 and provided with a vertical bore 35. The filling tubes hereinafter described are mounted on or operate in connection with a pair of plugs 36 and 37 adapted to be inserted in opposite ends of the bore 35 and provided with flanges to fix their inward positions. These plugs are held in place by a C-clamp having a body 38 with a lower portion bifurcated as at 39 to pass the filling tubes, and an upper portion provided with an adjustment screw 40 bearing against the upper plug 36. This arrangement makes the changing of filling stems for different sizes of containers a relatively simple matter. The body 10a is provided with a vacuum passageway 41 and a passageway 42 for the filling material; and these passageways are in turn connected to the chambers 12 and 13 of the main head by vacuum and filling material conduits indicated at 43 and 44.

The filling tube structure forming part of the filling head may take various forms. In the exemplary embodiment illustrated, as shown in Figure 5, the filling stem comprises an inner tube 45, which is the vacuum tube and has an opening 46 in the end thereof. This tube is inside a larger tube 47 which has side openings 48; and the arrangement is such that the tubes have no direct communication with each other.

The upper plug 36 is provided with a passageway 49 communicating with the vacuum passageway 41, the passageway 49 connecting at its opposite end with a central bore 50 in the plug 36. A tube 51 slides within this central bore and is provided with a gasket 52. A gasket 53 seals the upper plug against the inside of the vertical bore 35. At its lower end, the tube 51 terminates in an outwardly flared portion 54 adapted to snugly receive the inner tube 45 of the filling stem structure.

A large tube 55 slides in a perforation in the lower plug 37, and is provided with a sealing gasket 56. There is a fitting 57 closing the upper end of the tube 55 and bearing a gasket 58. A compression spring 59 is placed between the upper plug 36 and the fitting 57, the compression spring surrounding the necks 60 and 61 on the upper plug 36 and fitting 57, respectively. The tube 55 is provided with one or more perforations 62 near its upper end; and the arrangement is such that when the tube 55 is in the position shown in Figure 3, these perforations are exposed to the vertical bore 35. When, however, the tube 55 is lowered to a position in which the gasket 58 bears against the top surface of lower plug 37, the perforations will be closed by the lower plug 37. The tube 55 thus constitutes a valve for controlling the flow of filling material through tube 47.

The filling stem structure illustrated in Figure 5, i. e. the inner tube 45 and the outer tube

10

47, is connected to the tubes 51 and 55 by means of the coupling members 63 and 64. The outer tube 47 is connected to the coupling 63 and terminates substantially coterminous with the upper surface thereof; and the coupling member 63 is in turn connected to the coupling member 64 which is threaded to the tube 55. As will be evident from the drawings, the inner tube 45 extends upwardly beyond the end of the outer tube 47 and is received by the lower, outwardly flared end of the tube 51. By means of this arrangement filling stem structures of various lengths may be quickly and conveniently installed without having to disturb the filling head valving mechanism. Also, if desired, the tubes 51 and 55, and the couplings 63 and 64, may be eliminated and the tubes 45 and 47 of the filling stem prolonged so as to enter the head and serve as the valving means. In such instance changes in filling stems can be effected by removing the C-clamp 38 and lower plug 37.

The filling stem is designed to be raised by the container itself so that, if a container fails to be in filling position on the movable supports 5, there will be no flow of the filling material. As shown in Figures 3 and 4, I have fixed adjustably to the filling stem a stop member 65 having a sealing element 66 on its lower surface, serving both to effect the seal with the upper edges of the mouth of the container 6 and to cause the container itself to elevate the filling stem from the position shown in Figure 3 to the position shown in Figure 4.

As the container 6 is moved upwardly by the movable supporting means 5, the shoulders 67 of the bottle first contact the centering bell 68 carried by the annulus 69. The annulus 69 is in turn supported by a pair of rods 70 and 71 which are vertically slidable in the guideways 72 and 73 carried by the filling head 10a. It will be evident that as the container 6 is moved upwardly by the supporting means 5, the centering bell and annulus will move upwardly with it, the rods 70 and 71 sliding vertically in the guideways 72 and 73. Collars or studs 74 and 75 may be employed to determine the lowermost positions of the centering bell. While in the particular embodiment illustrated, the centering bell contacts the shoulders of the bottle; in other embodiments the centering bell might, by way of example, contact a ridge or flange formed on the neck of the bottle below its mouth.

The slideable rods 70 and 71 additionally carry a cross member 76 secured to the rods intermediate the annulus 69 and the filling head 10. A compression spring 77 surrounds the filling stem 47, and the spring 77 will be pressed between the stop member 65 and the cross member 76 when the filling mechanism is in the position illustrated in Figure 3. As seen in Figure 6, the annulus 69 carries a cam roller 78 adapted to be contacted by a cam track 79, the function of which will be explained hereinafter.

In operation, a container 6 on a movable support 5, occupying initially the position shown at A in Figure 2, is first moved upwardly, carrying the centering bell with it, until the mouth of the container contacts the sealing element 66 and moves the combination of tubes 45 and 47 upwardly against the compressive force of spring 59 contained in the filling head 10a. The mechanism thus assumes the position illustrated at B in Figure 2. In this position the outer or filling tube 47 will be connected through the orifices 62 to the vertical bore 35; and filling material

will flow into the container through the filling tube 47. The vacuum tube 45 will be connected at all times to the source of vacuum through the tube 51, bore 50, and passageways 49 and 41.

It will be noted that as the centering bell 68 is moved upwardly by the container 6, the cross member 76 carried by the rods 70 and 71 is moved out of contact with spring 77 so that the filling stem is solely under the influence of the spring 59; and the spring 59 is so selected that it applies only enough force to the filling stem to effect an efficient seal between the bottle neck and the sealing member 66. The spring is preferably so selected that it will apply substantially zero force in the extended position and the proper force for sealing only in the compressed position.

After the complete filling of the container, it is lowered, as seen at C and D in Figure 2, by the platform means so as to remove the filling stem from the mouth thereof. Simultaneously with the lowering of the container, the cam roller 78 carried by the annulus 69 comes in contact with the undersurface of a downwardly inclined cam track 79 which acts to lower the annulus and the centering bell, together with the rods 70 and 71 and the cross member 76 fixed thereto. As these parts are lowered, the cross member 76 comes in contact with the spring 77 causing it to compress, the spring supplying sufficient force to lower the filling stem and shut off the supply of filling material by closing the orifices 62. The cam 78 will pass from beneath the cam track 79 when the centering bell has been brought to its lowermost position. I have found that it is not necessary to hold the filling stems in the lowermost or closed position since the pressure in the vertical bore 35 is sufficient to hold the tube 55 in the lowermost position.

The arrangement just described enabled me to utilize the advantages of the pressure-vacuum principle without applying against the top of the bottle neck any greater pressure than is required to fill the bottle. As the bottle is raised into contact with the filling spouts, it is resisted only by the weight of the centering bell and the parts associated therewith. This weight, however, as can be clearly seen in Figure 4, is borne by the shoulders of the bottle adjacent the side walls thereof where the bottle is strongest. When the mouth of the bottle contacts the sealing member 66 to raise the filling stems to the filling position, it is resisted only by a force sufficient to cause proper sealing contact between the sealing member and the bottle mouth, the spring 59 being sufficiently light to apply only the necessary sealing force. The force required to lower the filling stems and thereby shut off the flow of filling material is supplied by the spring 77 which becomes effective only upon downward movement of the annulus 69 under the influence of cam track 79. At the time when the spring 77 becomes effective to apply force to the filling stem, the container 6 is being lowered by the supporting means 5 and will be out of contact with the sealing member 66. Consequently, at no time during the operating cycle of the machine is the container subjected to pressure great enough to cause it to be distorted or collapsed.

Modifications may be made in my invention without departing from the spirit of it. While I have described my filling head in connection with a pressure-vacuum filling system, it will be equally adapted for use in other types of filling

machines, as for example, in a machine employing super-atmospheric pressure only; and in the claims which follow it is not my intention to limit the invention to use solely in a pressure-vacuum machine. Having thus described my invention in an exemplary embodiment, what I claim is new and desire to secure by Letters Patent is:

1. In a filling machine, a filling spout structure comprising a body, a filling stem movable vertically relative to said body and having a free end extending beyond said body, a passageway effective through said body to supply filling material to said stem, said stem being movable from a lower position in which it is out of communication with said passageway to an upper position in which it is in communication with said passageway, sealing means on the free end of said stem for contacting the mouth of a container to be filled, whereby upward movement of said container will cause vertical movement of said stem, means effective when said stem is in its uppermost position to exert against said stem a force sufficient only to maintain said sealing member in sealing contact with the mouth of the container, and additional means effective upon filling of the container to supply sufficient additional force against said stem to return it to its lowermost position.
2. In a filling machine, a filling spout structure comprising a body, a filling stem movable vertically relative to said body and having a free end extending beyond said body, a passageway effective through said body to supply filling material to said filling stem, said filling stem being movable from a lower position in which it is out of communication with said passageway to an upper position in which it is in communication with said passageway, sealing means on the free end of said filling stem for contacting the mouth of a container to be filled, whereby upward movement of said container will cause vertical movement of said stem, spring means within said body effective when said stem is in its uppermost position to exert against said stem a force sufficient only to maintain said sealing member in sealing contact with the mouth of the raised container, and additional means effective upon filling of the container to supply sufficient additional force against said stem to return it to its lowermost position.
3. In a filling machine, a filling spout structure comprising a body, a filling stem movable vertically in said body and having a free end extending beyond said body, a passageway effective through said body to supply filling material to said filling stem, said stem being movable from a lower position in which it is out of communication with said passageway to an upper position in which it is in communication with said passageway, sealing means on the free end of said filling stem for contacting the mouth of the container to be filled, whereby upward movement of said container will cause vertical movement of said stem, spring means within said body effective when said stem is in its uppermost position to exert against said stem a force sufficient only to maintain said sealing member and sealing contact with the mouth of the container, a centering bell for the container being filled, said centering bell being supported on rods slidable in said body, said centering bell and rods being movable independently of said filling stem and adapted to be raised by said container together with said filling stem, means for lowering said centering bell upon filling of the container, and means in

connection with said centering bell for lowering said filling stem by supplying sufficient additional force against said stem to return it to its lowermost position.

4. The structure claimed in claim 3 wherein said means for lowering the centering bell upon filling of the container comprises a cam track acting upon a cam roller connected to said centering bell.

5. The structure claimed in claim 3 wherein said means for lowering the centering bell upon filling of the container comprises a cam track acting upon a cam roller connected to said centering bell, and wherein said means in connection with the centering bell for lowering said filling stem comprises spring means adapted to be compressed between said sealing member and a member carried by said rods during downward movement of said rods under the influence of said cam means.

6. In a filling spout structure including a body and a filling stem movable vertically relative to said body from a lower, non-filling position to an upper, filling position, said filling stem including a sealing member for contacting a bottle to be filled, force applying means within said body effective when said filling stem is in the upper, filling position to exert against said stem a downwardly directed force sufficient only to maintain the sealing member in sealing contact with the bottle mouth, and additional force applying means effective upon filling of the bottle to supply sufficient additional force to said filling stem to return it to the lower, non-filling position.

7. The structure claimed in claim 6 wherein said last mentioned force applying means acts upon said filling stem at a point remote from the point of application of said first mentioned force applying means.

8. The structure claimed in claim 6 wherein said first mentioned force applying means comprises a spring within said body contacting the upper end of said filling stem, said spring being compressed when said filling stem is in its upper, filling position.

9. The structure claimed in claim 6 wherein said first mentioned force applying means comprises a spring contacting the upper end of said filling stem, said spring being compressed when said filling stem is in its upper, filling position, and wherein said additional force applying means comprises a spring contacting said filling stem near its lower, free end, said last mentioned spring being under the influence of cam means effective to cause said spring to be compressed.

10. In a filling spout structure a body having a vertical bore, a filling stem movable vertically in said bore from a lower, non-filling position to an upper, filling position in which filling material under pressure is introduced into said stem through said bore, said filling stem including a sealing member for contacting a bottle to be filled, force applying means within said bore effective when said filling stem is in the upper, filling position to exert against said stem a downwardly directed force sufficient only to maintain the sealing member in sealing contact with the bottle mouth, and additional force applying means effective upon filling of the bottle to supply sufficient additional force to said filling stem to return it to the lower, non-filling position, said additional force applying means being releasable upon return of the filling stem to the lower-non-filling position, whereby said filling stem may be retained in the lower non-filling po-

sition by the pressure of the filling material in the said bore.

11. In a filling spout structure, a body, a filling stem extending downwardly from said body, a connection effective through said body to supply filling material to said filling stem, valve means for controlling the flow of filling material through said filling stem, said valve means being movable from a first position in which said filling stem is closed to the flow of filling material through said filling stem to a second position in which said filling stem is open to the flow of filling material, operating means associated with said filling stem for contacting a container to be filled to move said valve means from the first to the second position, pressure applying means acting to offer light pressure against the movement of said valve means to the second position, and valve return means effective upon the filling of the container to supplement said light pressure means and apply to said valve means sufficient pressure to assure the positive return of said valve means to the first position.

12. In a filling spout structure, a hollow body having a filling stem opening therein, a connection effective through said hollow body to supply filling material under pressure to said filling stem, valve means for controlling the flow of filling material through said filling stem, said valve means being movable from a closed position in which filling material is prevented from flowing through said filling stem to an open position in which filling material may flow through said filling stem, operating means for contact by a container to be filled to move said valve means to the open position against light spring pressure upon the juxtaposition of a container to said filling stem, and valve return means effective upon the filling of the container to exert sufficient additional pressure on said valve means to assure the positive return of said valve means to the closed position.

13. In a filling machine, a filling spout structure comprising a body, a filling stem extending downwardly from said body, a connection effective through said body to supply filling material to said filling stem, a sealing member on said stem for contacting the mouth of a container to be filled, said filling stem including valve means for controlling the flow of filling material through said filling stem, said valve means being operatively connected to said sealing member and movable upwardly, upon juxtaposition of a container to said sealing member and upward movement of the container, from a closed position in which said valve means is closed to the flow of filling material to an open position in which the valve means is opened to the flow of filling material, spring means effective upon upward movement of the valve means to exert relatively light spring pressure opposing the upward movement of the container so as to maintain said sealing member in sealing contact with the container being filled, and means effective upon downward movement of the container to exert sufficient additional pressure against said sealing member to cause said valve means to be positively closed.
